UNITED STATES PATENT OFFICE.

WILLIAM C. MICHAEL, OF CLAREMONT, NEW HAMPSHIRE.

CALCULATING-MACHINE.

Specification of Letters Patent. Patented July 20, 1915.

1,147,034.

Application filed July 14, 1909. Serial No. 507,517.

To all whom it may concern:

Be it known that I, WILLIAM C. MICHAEL, a citizen of the United States, and a resident of Claremont, in the county of Sullivan, State of New Hampshire, have invented an improvement in Calculating-Machines, of which the following description, in connection with the accompanying drawings, is a specification, like letters on the drawings representing like parts.

This invention relates to calculating devices and among other objects provides a mechanism which is simple in construction, efficient in operation and sufficiently small to be readily carried in the pocket of the user.

The character of this invention may be best understood by reference to the following description of an illustrative embodiment thereof shown in the accompanying drawing, wherein:

Figure 1 is a plan view of a calculating device embodying this invention; Fig. 2 is a similar view with the cover-plate removed; Fig. 3 is a vertical, central section taken on the line G—H of Fig. 2; Fig. 4 is a section taken on the line K—L of Fig. 2; Fig. 5 is a section taken on the line I—J of Fig. 2; Fig. 6 is a section taken on the line C—D of Fig. 2; Fig. 7 is a section taken on the line A—B of Fig. 2; and Fig. 8 is a section taken on the line E—F of Fig. 2.

Referring to the drawings, the illustrative calculating device embodying this invention comprises a cup-shaped casing 34 (Fig. 3), which may be conveniently formed of one piece of metal and is provided with a cover or face-plate 33 which may be secured to said casing by hollow corner rivets 37, 38, 39 and 40. Within this casing and directly beneath said face-plate is provided a disk 1 secured on the reduced end of a hub 13 (Fig. 3) journaled on a bearing stud 18 riveted or otherwise secured to the base of said casing and to the face-plate. On the outer face of this disk is a dial or scale consisting of characters arranged in the form of concentric columns each comprising herein a series of figures. The circular column nearest the hub of said dial (Fig. 2) herein consists of odd and even sixteenths from 1 to 16 and may be considered to represent the 16/16 of one inch; the next column consists of the odd thirty-seconds from 1 to 32/32; the next column consists of the odd sixty-fourths from 1 to 64/64; the next and out-

side column contains radially opposite each of the above fractions its corresponding decimal equivalent. Radially opposite and outside of each of these decimal equivalents is a perforation 54 which is adapted to receive the point of a stylus or pencil for turning the dial, as more fully hereinafter described. It will be observed that all of the numbers on this dial are fractions or their decimal equivalents and said dial may be referred to as the fraction dial.

It will be understood that this invention is not limited to the particular quantities or numerical values shown herein, but that other values may be readily used as desired.

Cooperating with this dial is a units dial 2 (Fig. 2), also inclosed within the casing 34 and is keyed to the reduced end of a hub 14 (Figs. 6 and 8), journaled on a hollow stud 19 connecting the base of said casing and said face-plate. On this dial in indelible figures is marked a circular column containing numbers from 1 to 10 and opposite each of these numbers is a perforation 56 adapted to receive the stylus or pencil point similarly as in the case of the dial 1. This dial 2 is adapted to turn one-tenth of a rotation for one complete rotation of the dial 1. To this end the latter is provided with a nosing or tooth 29 which herein is secured to said dial by suitable rivets 51 and 52. Once in each rotation of the dial 1 this tooth engages one of the teeth of a small pinion 4 (Figs. 2 and 6) secured to a stud 16 mounted in a bearing 21 which is secured to the bottom of the casing 34 (Fig. 6). The upward movement of said pinion is limited by its engagement with the under face of the dial 2. This pinion is adapted to engage the teeth of a gear 23 (Figs. 4 and 6) which is keyed to the reduced end of said dial hub 14 and rests on a washer 32 which is also keyed to said hub. The pinion 4 does not of itself turn the gear 23 one-tenth of a revolution but simply gives it an initial movement. To complete the one-tenth turn of said dial 2 the latter is peripherally notched (Fig. 2) to constitute a ratchet cooperating with a pawl 6 having a wedge-shaped nose 61 which is adapted to be pressed into the notches between the teeth of said dial by a leaf spring 10. As shown in Fig. 2 beneath the broken away portion of the dial 2, the teeth of the gear 23 are formed to permit the latter to be rotated in

dependently without engaging the teeth of the pinion 4, but when said pinion is rotated, as by the actuating tooth of the dial 1, one of the teeth of said pinion will enter 5 one of the notches 57 of said ratchet and will transmit an initial turning movement to the latter. This movement will cause the pawl 6 to be moved outwardly against the resistance of its spring until said pawl has passed 10 over the edge 81 of the next adjacent tooth whereupon said pawl will spring inwardly and complete the one-tenth turn of said dial. A curved faced pawl 8 (Fig. 2) pressed by a spring 12 clicks over the teeth 15 of pinion 4 and assists the dial tooth 29 to turn the pinion 4 one-fifth of a revolution and holds said pinion stationary with two teeth just clearing the teeth of the gear 23, as shown in Fig. 2, during the period when 20 said pinion is not engaged by said dial tooth and when said gear 23 is being independently turned to add or subtract units.

Within the casing 34 and adjacent the units dial is also a tens dial 3 (Fig. 2) which 25 is quite similar to the units dial described. This dial 3 is keyed to the reduced end of a hub 15 (Fig. 7) journaled on a hollow stud 20 which is secured to the face-plate 33 and to the bottom of the casing 34. Said dial 30 is adapted to be turned once in each complete rotation of the units dial 2 by a tooth 77 (Fig. 2) projecting from the washer 32 (Fig. 6) referred to, said tooth being adapted to engage an intermediate pinion 5 secured to the reduced end of a hub 17 (Fig. 7) which is journaled on a vertical stud 22 secured to the base of said casing. Any upward movement of said pinion is prevented by a suitable collar 26 on the outer end of 40 said stud 22. The pinion 5 is adapted to cooperate with a spring pressed actuating pawl 7 (Fig. 2) to turn a gear 24 (Fig. 7) mounted on the tens dial hub 15 and is spaced from said dial 3 by a suitable washer 45 25. These parts just described operate to turn the dial 3 one-tenth of a rotation for each complete rotation of the units dial 2 in a similar manner to that described for said dial 2 and similarly permit the dial 3 50 to be turned independently without turning the intermediate pinion 5. The pinion 5 is provided with a spring pressed pawl 9 (Fig. 2) which is adapted to click over the teeth of said pinion and position the latter in a manner similar to that described for pinion 4.

Having described the interior mechanism of the casing, I will now describe the construction and arrangement of the face-plate 60 33 referred to. This face-plate is cut away to form answer-openings 63, 64, 65 and 66 (Fig. 3) above the decimal equivalent column, sixty-fourths column, thirty-seconds column and sixteenths column respectively. 65 To permit the introduction of a stylus or

pencil point through the face-plate into the dial perforations 54, referred to, to turn said dial, said plate is provided with an annular opening 78 (Fig. 1), registering with and disclosing said dial perforations. This annular opening is not continuous but is interrupted as at 76 (Fig. 1) to form a stop 70 to mark the zero position of said dial.

The face-plate is cut away above the units dial to form an answer-opening 73, an annular opening 79, and a stop 74 for determining the zero position of the units dial. The face-plate is similarly cut away above the tens dial 3 to form an answer-opening 72, an annular opening 80 and a stop 75. 80

To centrally position the exposed numbers beneath the answer-openings 63, 64, 65 and 66 referred to, the dial 1 is provided with a positioning spring 45 which herein is secured to the base of said casing by rivets 85 46 and 47, and is provided at its outer free end with a knob 68 which clicks over the under ends of the perforations 54 in the dial 1 and effects the proper position of the latter. 90

To indicate the direction and degree of rotation of the dial 1, as more fully herein-after described, the face-plate 33 is provided with an index dial or scale (Fig. 1) consisting of characters arranged in the 95 form of concentric columns each comprising herein a series of figures. Adjacent the center of this index dial and above the sixteenths column of the dial 1 are two columns containing numbers from 1 to 16 inclusive, which may be considered to represent sixteenths of an inch, the inner column reading from 1 to 16 in a clockwise direction and the outer column reading from 1 to 16 in a contra-clockwise direction. The next 105 two columns contain odd thirty-seconds, the inner column reading in a clockwise direction and the outer column in a contra-clockwise direction. The next two columns contain odd sixty-fourths, the inner column 110 reading in a clockwise and the outer column in a contra-clockwise direction. Radially toward the periphery of the dial is the decimal equivalent of each of the fractions just referred to. 115

To facilitate the positioning of the stylus or pencil point in the perforations 54 opposite to the fractions near the center of the dial said fractions are repeated outside of the annular opening 78 and in some instances are reduced to lower terms and accompanying them are their denominators, such as 16, 32, etc.

On the face-plate above the units dial and outside of the annular opening 79 (Fig. 125 1) is marked indelibly two concentric columns containing numbers from 1 to 9 inclusive, one reading in a clockwise and the other in a contra-clockwise direction. The face-plate above the tens dial is similarly 130

marked with numbers 1 to 9 reading in a clockwise and in a contra-clockwise direction.

Having described the illustrative construction of the device, I will now describe its use. It may be supposed, for example, that it is desired to add $11/16$ and $49/64$. First insert the stylus point in the zero opening designated by the circle 69 (Figs. 1 and 2) of the dial 1 and turn said dial until said point engages the stop 76 (Fig. 1) to bring the dial to its zero position. Similarly turn the units dial 2 and the tens dial 3 to their zero positions by inserting the stylus point in the perforations designated by the circles 70 and 71 respectively. Now place the pencil or stylus point in the perforation 54 radially opposite number 11 in the contra-clockwise sixteenths column of the index dial, and turn the dial 1 in a clockwise direction until the stylus point reaches the stop 76 in the cover-plate, thereby bringing 11 beneath the answer-opening 66. The spring 45 will accurately position the numeral 11 centrally beneath said opening as described. The decimal equivalent .6875 of 11 will simultaneously appear under the answer-opening 63. Now place the pencil or stylus point in the perforation 54 radially opposite number 49 in the contra-clockwise sixty-fourths column and turn the dial 1 in a clockwise direction until the point of the stylus again strikes the stop 76 and comes to the zero point. By this movement the number 29 will appear through the opening 64 and through the units answer-opening 73 the numeral 1 on the dial 2 will appear and the machine will register 1 and $29/64$. The denominator of the fraction is 64 since the 29 appearing in the answer-opening 64, is in the sixty-fourths column. While the dial 1 was rotated in bringing the number 49 to the zero point the tooth 29 (Fig. 2) engaged the pinion 4 and rotated the latter one-fifth of a rotation; during this one-fifth rotation of pinion 4 one of its teeth engaged one of the teeth of the gear 23 and in combination with the pawl 6 turned the gear in a clockwise direction, together with its numeral dial, one-tenth of a rotation, as described, thus causing the numeral 1 to appear through the answer-opening 73.

Now, it may be supposed that it is desired to subtract $21/32$ from the above result, 1 and $29/64$. To make this calculation place the pencil or stylus point in the perforation 54 radially opposite number 21 in the clockwise thirty-seconds column and turn the dial 1 in a contra-clockwise direction until the point of the stylus strikes the stop 76, causing the numeral 51 to appear through the answer-opening 64, indicating $51/64$. The units answer-opening will read zero again, since the dial tooth 29 again engaged the

pinion 4, and rotated the latter in a clockwise direction which caused the gear 23 to rotate in a contra-clockwise direction one-tenth of a rotation and back to its original starting point-zero. The final answer is, therefore, $51/64$ and its decimal equivalent .79687 appears through the answer-opening 63. If, for example, it is desired to add $3 11/16$ and $49/64$, instead of $11/16$ and $49/64$ as before, insert the pencil point in the perforation 56 in said units dial radially opposite number 3 on the contra-clockwise index dial and turn the dial 2 in a clockwise direction until number 3 appears through the answer-opening 73. Then proceed as described above in the case of adding $11/16$ and $49/64$.

By this invention is provided a simple device for adding and subtracting whole numbers, fractions, decimals etc., by simply rotating the numeral dials clockwise or contra-clockwise without the necessity of any external attachments or adjustments, such as the shift-key hitherto necessary to change from addition to subtraction. The device is particularly advantageous for draftsmen and engineers in adding or subtracting whole numbers, fractions and decimal equivalents with speed and accuracy when checking up dimensions on drawings etc.

It will be understood that by using other numbers in the concentric circular columns other computations, such as multiplication and division, may be readily effected.

It will be understood that this invention is not limited to the particular embodiment shown herein and that various modifications may be made without departing from the spirit and scope of my invention.

Claims.

1. A device of the class described comprising, in combination, a dial having a driving tooth thereon, a dial of higher denomination having a ratchet and gear connected therewith, a pinion adapted to transmit an initial turning movement only from said tooth to said gear, said gear being movable independently of said tooth, and a spring pressed pawl co-operating with said ratchet to complete said movement.

2. A device of the class described comprising, in combination, a fixed index dial having concentric series of clockwise and contra-clockwise reading figures, movable dial means for adding and subtracting in succession selected figures on said dial, a second dial having concentric series of clockwise and contra-clockwise reading figures, a second movable dial means for adding or subtracting said figures, and means for moving said second dial means one step for each complete rotation of said first-named dial means, said means permitting the independent movement of said second dial means in any position of said first-named dial means.

3. A device of the class described comprising, in combination, a fixed index dial having concentric series of clockwise and counter-clockwise reading figures, movable dial means for adding and subtracting in succession selected figures on said dial, a second dial having concentric series of clockwise and counter-clockwise reading figures point-receiving formations in each movable dial to receive 10 a dial turning implement in the hand of the calculator, a stop formation also for each index dial to limit the movement of each movable dial with relation to a necessary indicating position on the fixed dial, and 15 means for moving said second dial means one step for each complete rotation of said first-named dial means, said means permitting the independent movement of said second dial means in any position of said 20 first-named dial means.

4. In a computing device, the combination with a plurality of movable dials of different denominations, each dial having a series of value indications thereon, fixed dials to which said movable dials are co-operatively related and means to transmit computing movement to a dial of higher denomination from a dial of lower denomination while permitting independent turning movement in either direction of the dial of higher 25 denomination in any position of the dial of lower denomination and without affecting the latter.

In testimony whereof, I have signed my name to this specification, in the presence of 30 two subscribing witnesses.

WILLIAM C. MICHAEL.
